UNITED STATES PATENT OFFICE

163,445

KNIFE HOLDER

Gilford Herbert Cushman, Minneapolis, Minn.

Application May 12, 1950, Serial No. 9,899

Term of patent 3½ years

(Cl. D44—29)

To all whom it may concern:

Be it known that I, Gilford Herbert Cushman, a citizen of the United States, residing at Minneapolis, in the county of Hennepin and State of Minnesota, have invented a new, original, and ornamental Design for a Knife Holder, of which the following is a specification, reference being had to the accompanying drawings, forming part thereof.

Referring to the drawings:

Fig. 1 is a view in perspective of a knife holder showing my novel design;

Fig. 2 is a view in side elevation; and

Fig. 3 is a view in perspective of the bottom side thereof.

I claim:

The ornamental design for a knife holder, as shown.

GILFORD HERBERT CUSHMAN.
